UNITED STATES PATENT OFFICE.

GEORGE A. ROBINSON, OF QUINCY, MASSACHUSETTS, ASSIGNOR, BY MESNE ASSIGNMENTS, TO STATE STREET TRUST COMPANY, TRUSTEE, OF BOSTON, MASSACHUSETTS, A CORPORATION OF MASSACHUSETTS.

METHOD OF TEMPERING PAPER LABELS.

Application filed January 6, 1921. Serial No. 435,489.

To all whom it may concern:

Be it known that I, GEORGE A. ROBINSON, a citizen of the United States, residing at Quincy, county of Norfolk, State of Massachusetts, have invented a certain new and useful Improvement in Methods of Tempering Paper Labels, of which the following is a specification, reference being had therein to the accompanying drawings.

10 The invention relates to a new and useful method of treating paper labels which are to have adhesive applied to them and which are to be immediately affixed to the package before the adhesive dries. If the label is dry when the adhesive is applied to it, there is a tendency of the label to curl after it is gummed and there is also a tendency for the label to stretch after it has been gummed. The object of the present invention is to treat the label before being gummed in such manner as to avoid any curling of the label and also to cause the stretching to take place before the adhesive is applied so as to prevent any stretching 25 of the label after the application of the adhesive. Attempts have been made to accomplish this result by moistening the label before the adhesive is applied, but as heretofore practised the results have been very 30 uncertain owing to the fact that different grades or quality of paper vary in the coefficient of absorption of moisture. It is important that before the adhesive is applied to the sheet the water shall penetrate 35 entirely through the paper so that all the fibres of the paper are moist, otherwise the paper still has a tendency to curl instead of lying flat, and moreover the paper continues to stretch, which is a condition we wish to 40 avoid. On the other hand if the paper is left in the water longer than the time required for the moisture to penetrate all of the fibres, then the paper begins to disintegrate and the fibres pull apart, thus 45 spoiling the label. It is also important that there should not be any film of water on the surface of the paper at the time the adhesive is applied, otherwise the adhesive does not strike the paper at all, that is if 50 there is a film of water between the adhesive and the paper it prevents the label from adhering properly to the package. It is therefore important that the paper label should receive just the requisite quan-

tity of water to penetrate entirely through 55 the paper and no more, and that it should not be left exposed to the bath any longer than the length of time required for the water to penetrate the fibres, as already described. Every grade of paper apparently has a definite coefficient of absorption 60 which is constant at all times, but as already stated the coefficient varies with the different grades, qualities or kinds of paper.

I have found that as the temperature of 65 the water is raised the moisture penetrates the paper much faster; therefore, the temperature and the length of time to which the label is subjected to the water bath should be so determined or should bear such relation to each other that the water will have 70 time to penetrate entirely through the paper and no more, before the adhesive is applied. This will cause the paper to stretch and prevent its curling. When this is done the 75 paper is so tempered that any additional moisture such as may be contained in the adhesive which is applied to the label immediately after the label is moistened will not cause any further stretch in the label. 80

It is important that the temperature of the water should be below the vaporizing point and also that it should be at a temperature as high as the ordinary room temperature. Best results are obtained when 85 the temperature of the water is not below 90° and not higher than 180°.

With the water at a certain temperature, 90 a paper of certain grade or coefficient of moisture should remain immersed a predetermined length of time. The lower the temperature, the longer time it should remain in the tank. In other words, stated in the form of an equation, if T equals the length of time, X equals the temperature, 95 and C equals a constant, then the product of $T \times X$ equals C in all cases, so that the temperature and the time must vary in inverse proportion as either is varied. The constant, however, varies as the coefficient 100 of absorption of the paper, and this coefficient must be determined before determining the other elements, that is the length of time and the temperature.

It is important that once this coefficient 105 and constant are determined, all of the labels of a particular grade should be treated exactly alike, at least that C should always

2
be the same, so that if T is varied, X should be varied inversely, so that the product C will always be the same.

It is extremely difficult, in fact practically impossible, to get this uniformity by hand work. In order to get the uniformity it can best be done mechanically and the best method of accomplishing this known to me is to cause the labels to travel through a tank of water, being fully immersed in the water in the passage through the tank, and upon emerging from the tank the surface water should be removed, as for instance by passing a label between rolls which have a very slight wringing pressure upon the paper, and then the adhesive should be applied to one face of the label. The label is then ready to be applied to the package.

Means should also be provided for maintaining the water at the temperature desired, and the carrier which carries the label through the tank should be caused to travel at a predetermined rate of speed. A thermometer should be provided within the tank so that the temperature of the water can at all times be determined, and means should be provided for controlling the temperature of the water so as to maintain it at a constant temperature. Any suitable means for treating and controlling the temperature may be employed. One means consists of a valve controlled steam pipe or pipes extending into the tank. Now if the constant, that is C , has been determined in advance and the speed of the carrier is known, which speed is determined by the rate of delivery of the sheets of paper to fulfill the requirements of subsequent steps in the manipulation of the previously prepared sheets, then the temperature of the water should be maintained at such a degree that $T \times X = C$.

It will thus be seen that once the coefficient is determined, then so long as the same quality of labels is employed an exact uniformity of the product is obtained by simply maintaining the predetermined temperature of the water and speed of the carrier.

Any suitable form of label carrier and tank and means of determining the temperature of the water may be employed, as my invention does not consist in the mechanism for carrying out the process but in the process itself. Therefore I do not deem it necessary to show the mechanism in full

detail in the drawings, but only so much as is sufficient to clearly illustrate the process.

The drawing is a diagrammatic view of a machine by which the process of the invention may be practised.

Referring now to the drawing, the tank 1 contains water of suitable depth, the level of the water being shown at 2. A steam pipe 3 provides means for heating the water, and the admission of steam can be controlled and regulated by a valve 4. A thermometer 5 within the tank indicates the temperature, the tank having a glass side so that the thermometer can be easily read.

The paper labels are fed from a table 6 to be gripped between two carrier belts 7, 8 as the belts converge after running over the guide rolls 9, 10. The carrier belts run over guide rolls 11, 12 in the tank, and carry the labels down into the water in the tank and out again, thence over the guide roll 13, and then deliver the labels to a support 14.

As there may be a film of water on the surface of the label when it is removed from the tank, it is best to have this surface water immediately removed, so that it will not cause an excess saturation of the label nor the water be left as a film on the surface when the adhesive is applied. Any suitable means may be employed for removing this film from the surface without injuring the paper. The preferred means is to pass it between wringer rolls 15, 16 to which it is delivered from the support 17.

The adhesive may be applied in any suitable way, either by hand or mechanically. A convenient method is to apply it mechanically, for instance by causing the label to pass from the wringer rolls 15, 16 across a support 17 into contact with a gluing roll 18. The gluing roll is shown as dipping into a glue pan 19.

What I claim is:—

The herein described method of tempering labels which consists in determining the coefficient of absorption of the paper of which said labels are composed and immersing them for a constant time in water at a temperature conforming to the formula: $T \times X = C$; wherein T represents the constant time, X the temperature, and C the coefficient of absorption.

In testimony whereof I affix my signature.

GEORGE A. ROBINSON.
